COMPUTING APPARATUS

Charles J. Goodale, 29 George St., Springfield, Mass.
 Original application June 8, 1953, Ser. No. 360,121, now
 Patent No. 2,928,595, dated Mar. 15, 1960. Divided
 and this application Mar. 8, 1960, Ser. No. 13,608
 5 Claims. (Cl. 200—92)

The present invention relates to apparatus capable of carrying out computing methods wherein mechanical movements may be largely replaced by electronic devices. This application is a division of the copending application Serial No. 360,121, filed June 8, 1953, now Patent No. 2,928,595, dated March 15, 1960.

Some of the main objects of the invention are to provide, such as for purposes of apparatus according to the above patent, apparatus for carrying out algebraic summations by means of scale elements, and to provide computing apparatus which performs quickly and reliably mathematical operations, especially such summations.

Other objects of the invention are to provide an accounting machine which performs its operations in simple and yet reliable manner, unhampered by requirements introduced by complicated counting and accumulating procedures and accordingly more or less complicated mechanical gear; to provide a computing machine which materially reduces the length of time between the recording of collected data, and the evaluation thereof at the same or another place; to provide a computing machine which is composed of operating units which are only electrically interconnected, so that they can be easily rearranged and combined to form complete machines suitable for various purposes; to provide apparatus of this type which furnishes final data without any preliminary or subsequent sorting operation of the records from which this data are collected and without the necessity for highly manual preparatory work, which sorts automatically by way of a source recorder or subordinate unit, and which furnishes these data in a minimum period of time from the first recordation thereof; and to provide computing apparatus of this type which eliminates any need for reading, copying, or transcribing steps intermediate the initial collecting of the data concerned, and the final evaluation thereof.

Further objects of the invention are to provide fully effective and reliable apparatus for defining and putting into effect the shifting reference principle used according to my above mentioned patent, to provide effective and simple apparatus for translating accumulated data into a visible record, to control the computing operations of the machine by means of counting and operational indicia and sequence indicia combined in a manner which renders these operations speedy, reliable and practically independent of irregularities of the indicia, and to provide electrically controlled and actuated means for shifting counting elements, for operating contact controlling elements, and for operating printing mechanisms in a particularly simple and effective manner.

In one of the aspects of the invention, the above objects are attained by coupling one or the other of two counting members to an actuating means which is adapted to advance stepwise in a given direction under the control of sequence indicia, and under the control of means for coupling one or the other counting member to the actuating means under control of and during steps determined by counting indicia conjointly with the sequence indicia, means being in addition provided which are controlled by operational indicia for selecting one or the other of the counting members for coupling by

2

means of the counting indicia to the sequence indicia actuated stepping means; one of the counting members is provided with means, such as electric contacts which are part of a relay circuit, for indicating the relative position of the two counting members independently of their position regarding the machine considered as a mechanical structure.

Additional features of the invention include magnetically controlled movements which serve as clutching and switching elements and operate by shifting a coupling member from a permanent magnet fastened to one of two relatively movable elements to an electrically controlled magnet fastened to the other element which may be a rotatable shaft; commutator switches with circular contacts whose angle relation conforms to the operational relation of the above mentioned counting members and permits a wide range of correlation of computing operations as controlled by the record indicia; and an arrangement for printing computation results by means analogous to the accumulating means.

These and other objects, aspects and features will appear from the following description of a typical practical embodiment illustrating the novel characteristics of my invention. This description refers to drawings in which

FIGS. 1 and 2 represent a view, partially in axial section, of the accumulator unit of the apparatus shown in FIG. 1 of my above-identified patent;

FIG. 3 is a section on lines 3—3 of FIG. 1;

FIG. 4 is a section on lines 4—4 of FIG. 3;

FIG. 5 is an exploded isometric view of the clutch mechanism shown in FIGS. 1 and 2;

FIG. 6 is a section on lines 6—6 of FIG. 1;

FIGS. 7 and 8 are elevations showing the contact faces of the commutator switch disks shown in FIG. 1;

FIGS. 9 and 10 are schematic combined views of the commutators shown in FIGS. 7 and 8, in two characteristic positions;

FIG. 11 is a vertical section through the printing unit of the apparatus according to the invention;

FIGS. 12 and 13 are elevations showing the contact faces of the commutator switch disks shown in FIG. 11; and

FIG. 14 is a schematic combined view of the commutators shown in FIGS. 12 and 13.

Apparatus according to the present invention lends itself very well to unit construction and to the assembly of unit elements, each performing its particular function, in operational combinations and spatial set-ups selected according to individual requirements. While the embodiment herein described represents a machine that performs operations satisfying average computing requirements, it should be understood that it can be used as an element of apparatus fulfilling different, perhaps more elaborate, requirements and that its units and elements can be employed in combinations other than that herein referred to.

Accumulator units according to the invention can be conveniently mounted on base board 101 which may be fastened to the main base plate 31 of the cabinet, with side frame boards 102 and 103, as indicated in FIGS. 1 and 2 which together constitute a single view, partly in section, of the accumulator assembly. The movable portions of the accumulator are guided upon or fastened to a shaft 105 which is journaled in frame walls 102 and 103 by means of ball bearings 108 and 109.

The shaft 105 can be rotated in steps of prearranged magnitude, by means of stepping or sequence solenoids Z1, Z2, Z4 (FIGS. 1 and 2) each of which consist of a magnet winding 111 and a housing 112 fastened to plate 101 by brackets 128. Into housing 112 are screwed

holding plates 115, which secure the coil within the housing, and also determined, by means of rims 116, the travel of armature plungers 118 which are by means of rods or links 119 and one way couplings 120 joined to shaft 105. As shown especially in FIG. 4, couplings 120 may be ball clutches consisting of two bearing rings 121, 122, and therebetween a clutch ring 123 which has a cam recess 124 confining a ball 125 between its face and the shaft 105. As well known, the clutch body will be attached to shaft 105 only when it rotates in the direction indicated by the arrows of FIGS. 1 and 4, whereas the shaft is released when the clutch body is rotated in the opposite direction. Thus, the shaft 105 is rotated through steps corresponding to the stroke of each respective plunger if the latter moves in the direction of the arrow of FIG. 3. It will be observed that rotation of shaft 105 by solenoid Z1 will not affect the other solenoids whose one way clutch will then be idle, and vice versa. As indicated in FIG. 3, the strokes of solenoids Z1, Z2 and Z4 are stepped in the ratio 1:2:4. The plunger of solenoid Z2 floats, but its length is so selected that, when de-energized, it permits the plunger of solenoid Z4 to assume its full stroke, whereas when Z2 is energized, its plunger advances to an extent which presets the stroke of the plunger of Z4 to one-half of its full value. Hence, (a) the stroke of solenoid Z2 pushing the plunger of de-energized solenoid Z4, (b) the stroke of solenoid Z4 as preset by solenoid Z2, (c) the stroke of solenoid Z1, and (d) the normal stroke of solenoid Z4 as shortened by the previous stroke of solenoid Z2, bear the ratio relation of 2:2:1:4. As will be fully explained hereinbelow, these strokes are affected by appropriate circuit control, their four values correspond to those of the four counting code marks discussed above with reference to FIGS. 7 and 8, and they permit the definition of any one of the nine digits in any decade position.

The accumulator unit further contains a number of digit counter sets which are in this art sometimes also referred to as accumulator sets, one for each order or position. Only two of these sets are shown in FIG. 1, namely the "units" and "tens" counter sets. Each counter set consists of two permanent magnets 131, 132, which have bores permitting shaft 105 to rotate freely therewithin, and which are fastened to base plate 101 by brackets 134. Fixed to shaft 105 are core bodies 135, 136 of magnetic material. Solenoid coils Za and Zs, mounted on brackets 165, surround core bodies 135, 136 and define gaps 160. Rotatably connected to shaft 105 by means of ball bearings 141, 142 are two clutch sleeves 143, 144, each of which carries a commutator disk, indicated at 145 and 146, of insulating material, and has a coupling slot, indicated at 155, 156, compare also FIG. 5.

These commutator disks carry, riveted or otherwise fastened thereto, five concentric contact sectors s1, s2, s3, s4, s16 and companion sectors s11, s12, s13, s14 and s15 as indicated in FIGS. 7, 8 and 9. The contact sectors of the respective commutator disks are in sliding contact making engagement while in coinciding angular position. It will be noted that FIG. 7 is a view seen from the right-hand side of FIG. 1, whereas FIG. 8 is a similar view seen from the left-hand side of FIG. 1; FIG. 9 shows the commutator contacts of both disks in super-imposed position, seen from the left-hand side of FIG. 1. As indicated in FIG. 7, the angular distance between the extreme ends of the commutator contacts s1, s2, s3, s4, s16 of disk 145 is 36°, that is $1/10$ of the entire circumference, and corresponding to a step of value "1." Ten equidistant points of the circumference of this disk define ten digit positions, from 0 to 9, as likewise indicated at FIG. 7. The ends of the contact segments s11, s12, s13, s14, s15 of commutator 146 are similarly defined, as indicated in FIG. 8. The respective disks 145 and 146 rotate, when coupled to shaft 105, in the same

direction, as indicated by the arrows applied to the respective figures.

Between permanent magnets 131, 132 and cores 135, 136 are arranged coupling slides 151, 152 which have two claws or prongs 153 engaged in the above mentioned slots 155, 156 of clutch sleeves 143, 144. The last mentioned two elements are isometrically shown in FIG. 5. The two slots 155, 156 engage the two claws 153 permanently, although the latter can move axially therewithin, so that, when coil Za is de-energized, disk 151 is attracted to permanent magnet 131 retaining sleeve 143 immovable with regard to the frame. On the other hand when coil Za is energized, the attractive force of the permanent magnets is overcome and disk 151 is attracted by core 135, which, it will be remembered, is fast to shaft 105, so that claws 153 will now move sleeve 143 with them. In the first mentioned instance, namely with disks 151 or 152 fast to permanent magnets 131 or 132 (which are mounted on the apparatus base), sleeves 143 or 144 are fixed relatively to the base but permit rotation relatively to shaft 105 on ball bearings 141 and 142; in the last mentioned instance, namely when coils Za or Zs are energized shaft 105 and disks 143 or 144 rotate together. As will appear hereinbelow, Za and Zs are never simultaneously energized.

On radii corresponding to those of the commutator segments s1 to s5 and s11 to s15, are arranged, on the outside of disks 145 and 146, collector slip rings 170 which are conductively connected to the commutator segments, for example by the above mentioned rivets. These rings cover uninterruptedly the entire 360° arc of the disks, and continuously contact individual brushes 180, as indicated in FIG. 1.

As mentioned above, the accumulator has a counting set for each digit position; in the present instance five sets would be provided although only two are shown in FIG. 1.

The accumulator also has several relay units, which are shown in FIG. 2.

The switching elements of these relays may assume various forms, whereas their actuating structures are essentially similar, as will now be explained with reference to FIG. 2. This figure indicates at 171 and 172 permanent magnets which are fastened to base 101 by means of brackets 175 and 176. Core supports indicated by numeral 181 are fastened to base 101 with brackets 185 and have guiding slot portions 186. They carry contact bases 187 of insulating material. Coils Zop, Zos and Zoc are fastened to base 101 by means of brackets 165 and form gaps 195 with cores 192 of magnetic material that are fastened to core bodies 181. Within the gaps 195 move contact carriers 194 which are similar to the coupling elements shown in FIG. 5, with the difference that one claw or if desired each claw carries contacts 198 or contact bridges 199. As indicated in FIG. 2, there may be contact bridges on either side of the movable claw of switch element 197, or one of several contact pairs to be connected by these bridges, may be arranged on one or either side of the movable claw. The various contacts shown in FIG. 2, are not individually identified because they correspond to those identified and described in detail with reference to the circuit diagram Fig. 20 of my above identified patent. It will now be evident that energization of coils Z moves the switching bridges such as 194, 197 in the direction of the axis of shaft 105, while de-energization causes them to be attracted by the permanent magnets. This mode of actuation is quite similar to that of the accumulator and commutator sets, and permits use of similar parts for both types of mechanism.

It will be evident that various clutches and switches can be constructed in similar manner, in accordance with varying circuit requirements, and arranged in compact units as indicated by FIGS. 1 and 2.

The recorder unit is arranged in a suitable compart-

ment and mounted on a base plate 201 and on frame walls 202, 203 and 204 (FIG. 11), with the base plate 201 secured to the main base plate 31 of the cabinet. In a space formed by walls 203, 204 and by a printing base plate 205 is mounted a printing device with a hammer solenoid Z_h which is adapted to lift, when energized, a printer hammer 211 against the underside of recording card 200, inserted through a suitable slot between guides 215 and 216. The stepped upper portions of the cabinet form a feeding platform provided with indicating lines which permit registration of the card 200 with the printing mechanism. The card may be discharged through a slit in the rear wall of the cabinet. An ink ribbon 221 carried by rolls 222 and 223 supplies printing medium in well known manner. When hammer 211 is lifted, it presses card 200 against ribbon 221 and the type wheels to be described hereinbelow, thus recording the number defined by the type wheel digits.

A shaft 205 is journaled in side walls 202 and 203 by means of ball bearings 228 and 229. This shaft performs a function similar to that of the above described accumulator shaft 105 and can be rotated stepwise by means of solenoids Zp_1 , Zp_2 and Zp_4 which are in the present embodiment identical with the accumulator solenoids Z_1 , Z_2 , Z_4 described with reference to FIGS. 1 and 3, and advance the shaft through the corresponding steps of 36°, 72° and 144°. In order simplify FIG. 11, only one solenoid Zp_4 with its clutch 120 is shown.

The shaft 205 is further associated with a number of clutch elements, one for each order or position, which are similar to those described with reference to FIG. 1, with the only difference that they are equipped with gear wheels 231 in addition to the commutator disks 233, and that stationary commutator disks 235 are fastened to the energizing coils C_p . It will be noted that gear wheels 231 rotate whenever coils Z_p are energized while shaft 205 turns, coupling the bearing supported switch and gear wheel sleeves 238 to cores 242 which are fixed to shaft 205. This also provides selective rotation of the commutator disks 233.

The stationary commutator disks 235 have two concentric contact rings s_{22} , s_{23} with gaps extending through 36°, as shown in FIG. 12, while the rotatable disks have two contact segments, s_{25} , s_{26} , covering an angle somewhat smaller than 36°, as shown in FIG. 13. FIG. 14 shows the two disks in superimposition. The arrows applied to FIGS. 11, 13 and 14 indicate the respective directions of rotation, it being assumed with respect to FIGS. 13 and 14 that these figures show the contact faces of the disks of FIG. 11. The contact elements of these commutator switches are also shown in FIG. 20 of my above-identified patent and their function is explained therein.

A supporting rod or stationary shaft 245 is fastened to frame walls 202 and 204 and carries several hollow shafts, one for each type wheel and hence one for each order position which the machine in question is required to handle. In the present instance five type wheels 251 to 255 are shown which are correspondingly fastened to hollow shafts 261 to 265. Each type wheel is supplied with raised type numbers 0 to 9, opposite the above mentioned ribbon 221. The other ends of shafts 261 to 265 are fast to gear wheels which mesh with the gear wheels 231 of the printer clutch units. FIG. 11 shows only two of these gear wheels, namely 271 and 272; it will be understood that each type wheel has one of these gear wheels which again are associated with the appropriate number of clutching and commutator switching units, each with permanent magnet 241, core 242, coil Z_p , commutator disk 235 and rotatable sleeve 238 with gear wheel 231 and commutator disk 233.

It should be noted that the digit numbers of the type wheels run in reverse direction as compared to those of

the accumulator wheels (as indicated in FIG. 7), having in mind the respective sense of rotation of these elements.

The operation of the above described apparatus is as follows:

5 The solenoid Z_2 which, as above described, rotates, when energized, the shaft 105 (FIGS. 1, 2 and 3) by way of the armature of solenoid Z_4 , through an angle of 72° which defines the number value "two" and corresponds to the first code mark. The sequence tubes G_2 and G_4 10 are connected to solenoids Z_4 which, as above described, is so arranged that it turns, if solenoid Z_2 is energized at the time of energizing Z_4 , the shaft 105 through an angle defining the number value "two" whereas if not limited by solenoid Z_2 , it turns the shaft through an angle 15 of 144° defining the value "four." The sequence tube G_3 is connected to solenoid Z_1 which is adapted to rotate shaft 105 through an angle of 36° defining the number value "one."

As above described, tube G_5 is connected to a solenoid 20 Z_{oc} which operates the switch s_{71} for connecting line B to the commutator switches K_a . Tube G_5 is further connected to solenoid Z_h which operates the printer hammer.

While the accumulator solenoids Z_1 , Z_2 , Z_4 are directly connected to line A, the hammer solenoid Z_h and the printer solenoids Zp_1 , Zp_2 and Zp_4 are connected to an auxiliary bus A_{31} , which leads to contacts s_{31} of switch Z_{op} , as above described. It will be remembered that the accumulating solenoids Z_1 , Z_2 , Z_4 are energized every time one of the first four slits 43 passes light through 30 conductors 91, 92, rendering photo tube P_t more conductive, and, with some time delay caused by network R_4 , C_4 , rendering the tubes G_1 , G_2 , G_3 , G_4 and G_5 consecutively conductive; the multi-vibrator tubes V which operate the accumulating magnets are energized some- 35 what before the sequence solenoids become active.

Observing now for example the accumulation of number "56789" of a record strip, it will be noted that the first two code marks of the order or column defining digit "5" are blank so that, although the first two sequence slits 40 will operate solenoids Z_2 and Z_4 respectively and correspondingly rotate the shaft 105, the coupling magnets of the "ten thousand" set of the accumulator will not respond and the corresponding accumulator disks will remain stationary. The third code mark of the "ten thousand" 45 column will render its tube V conductive, and the third slit will shortly thereafter energize sequence solenoid Z_1 . The rotating shaft 105 thus finds the tens of thousands order counting disk connected thereto, and since solenoid Z_1 defines the unit 1, the counting disk will be advanced 50 one step, through 36°. The code mark of the next row similarly affects the "10,000" counting tube and the corresponding fourth slot energizes sequence solenoid G_4 , causing the accumulator disk to advance four number values. This, together with the previous single step, defines the digit "5." Similarly, the digit 9 in the "unit" 55 position of the above referred to number "56789" will be accumulated by consecutive energization, four times, of counter coupling magnet which connects the corresponding accumulating disk to shaft 105 each time one of the three sequence solenoids rotates the shaft, so that the disk will be advanced first two number values, then again two values, then one value, and then finally four values, together nine values. In this connection it should be remembered that solenoid Z_2 is energized immediately 60 prior to energization of solenoid Z_4 and that Z_2 is not de-energized until Z_4 becomes energized. Thus the stroke of the actuator moved by solenoid Z_4 will start from the point to which it was previously advanced by solenoid Z_2 , and this energization of Z_4 therefore affects but a 65 two step advance of shaft 105.

The above discussed steps are defined by the position of the accumulator disk 145 (FIG. 1), with regard to that of the home or zero point of the subtracting or reference disk 146.

75 It will be noted that for the above described "adding"

operation, the switch Z_{0s} is in the position shown in Fig. 20, of my above-identified patent, with contacts $s51$ closed, and contacts $s52$ open. Switches Z_{0p} and Z_{0c} are likewise in the position shown in Fig. 20 of my above-identified patent. The commutator contacts of the several accumulating sets move relative to each other, but this movement has significance only when the nine to zero region of the accumulator disk 145 coincides with the home point of the reference disk 146, as will be presently explained.

For subtracting, the above described apparatus utilizes a novel procedure which is illustrated in Figs. 21, 22 and 23 of my above-identified patent, and the general principle of which will now be described.

This subtracting method is based on the concept of a "floating home" or "advancing zero" position of the subtraction and reference element, as described in my above-identified patent.

If the computation results are to be mechanically or otherwise recorded some means have to be used for rendering the mechanical position of the floating zero or home independent of its actual meaning with regard to the computing operations. The apparatus according to the present invention exemplifies such an arrangement in the commutator arrangement particularly illustrated in FIGS. 7, 8, 9 and 10. As will be described hereinbelow more in detail, this arrangement permits detection and evaluation of the relative position of the counting elements, independently of their mechanical relation to the physical structure of the apparatus.

One possibility, likewise in accordance with the present invention, of subtracting by means of the floating home method will now be described.

The subtracting operation is initiated by means of a subtraction defining operational mark which attaches a respective subtracting and floating home element 146 (FIG. 1) to shaft 105 and similar operations simultaneously take place for the digits in the higher positions. After the entire number to be subtracted has thus been evaluated, the end of the subtraction mark causes connecting of the adding clutch magnets Z_s instead of the subtracting clutch magnets Z_s . If a further number is to be subtracted, its code marks would again be accompanied by a subtracting mark which would maintain the subtracting clutch magnets in operation, and again cause the subtracting and reference disks 146 to be attached to shaft 105, instead of the adding disks 145.

It is again emphasized that in accordance with my new subtracting principle, both adding and subtracting elements move always in the same direction, as pointed out above when relating the movement of disks 145 and 146 to shaft 105, which, of course, is rotated always in the same direction by solenoids $Z1$, $Z2$, and $Z4$.

The reference point, namely point 0 of disk 146 (FIG. 8), rotates in the same direction around shaft 105, but the relative position of the adding and subtracting elements or disks is evaluated by means of the commutator, whose operation will be described in detail hereinbelow, under the heading "Total Taking." It will also be noted that the possibility of actuating the adding and subtracting disks by the same stepping solenoids, is due to the fact that they move in the same direction.

Coming now to the carry-over operation, this has to take place whenever an accumulating element moves from its position 9 to its position 0 relatively to the zero or home point. In the present instance, where co-directionally moving counting elements are used for algebraic summation as well as for defining the home point, the carry-over operation has to take place whether due to movement of the positive, that is adding, or the negative, that is subtracting and reference disk. Whenever the point 9 of an adding disk is about to move to bring the zero point of that element into coincidence with the floating home point of its reference and subtracting element, whether this is due to the movement of the adding or the subtracting

disk, a carry-over operation must be carried out for bringing about a change of digit value "one" in the next higher order. There is, however, one distinction, namely this change of one value in the next higher order has to be an increase when caused by an adding operation in the lower order, but decreased when due to a subtracting operation in the lower order.

In the present embodiment of my invention, the carry-over operation is carried out by means of the commutator construction shown in detail in FIGS. 7 to 10. The correlation of the two commutator disks 145 and 146, in normal or starting condition for a carry-over, is indicated in FIG. 9, which is repeated in the circuit diagram of FIG. 20 of my above-identified patent which, however, does not show the entire contact $s11$, although the continuity of that contact is indicated by joining its broken off end to point 321 of the next higher group of circuit N_c . The carry-over operation is first set up for each unit in which the above described progress from "9" to "0" takes place, but it is actually carried out by means of the capacitor indicated at $C40$.

Referring to FIGS. 7 and 8, it will be noted that the commutator contacts $s1$ and $s2$ of disks 145 are electrically connected and normally in contact with contact $s11$ of the reference disk 146 which contact $s11$ is only interrupted through the partial length of one unit, following the position of the home or zero point. As described in my above-identified patent, the contact $s11$ is at 321 connected to the grid of the clutch switching tube of the next higher group, contact $s11$ of the "units" set being connected to the "tens" tube V_t , whereas the contact $s11$ which goes with V_t is analogously connected to the grid of tube for the "hundred" digits, and so on. Normally (that is excepting the period from the time when point 35 "nine" of the adding disk passes from the "home" point of the other element, until point "zero" of this adding element reaches the "home" point) a capacitor is enabled to discharge through the connection $s1$ — $s2$ — $s11$. The complete discharge circuit of capacitor $C40$ is $C40$ — $s11$ —321— Pit — B — $s72$ — $C40$. FIG. 9 shows the superimposed commutator disks (seen from one side as if transparent and hence rotating in the same direction as indicated by the arrows) in the "adding" position when point nine of the adding disk 145 (FIG. 7) coincides with the home point of the subtracting disk 146 (FIG. 8), further rotation of the adding disk bringing both zero points into coincidence. Contact $s3$ of the adding commutator disk is normally open when the point "nine" of that disk reaches "home." After point 9 of the adding disk passes "home," $s1$ — $s2$ become disconnected from $s11$ and instead connected to $s12$ (on bus A). At the same time the normally open commutator contact $s13$ of the other disk is connected to commutator contact $s13$ of the other disk which is through contacts $s42$ connected to the bus B , with relay Z_{0p} in the normal position shown in FIG. 20 of my above-identified patent. It should be noted that capacitor $C40$ is normally disconnected from line B by switch $s71$ which is operated by condenser $C0$ under control of solenoid Z_{0c} . This solenoid Z_{0c} is energized when stepping tube $G5$ becomes conductive, due to the effect of the fifth sequence mark 49. With commutator contact $s13$ thus connected to the negative bus B , and with commutator contacts $s1$ — $s2$ connected to the positive bus A , capacitor $C40$ charges in circuit $s12$ — $C40$ — $s3$ — $B12$ — $s42$. The disks 145 and 146 continue their relative movement until contact $s3$ of adding disk 145 again leaves contact $s13$ of reference disk 146, so that capacitor $C40$ is now disconnected from the negative bus B , retaining its charge. With the two commutator disks further continuing their relative movement, contact $s1$ and with it contact $s2$ comes into contact with $s11$ of the reference disk just before the "0" position of adding disk 145 reaches "home" position of disk 146. This position is shown in FIG. 10.

Keeping in mind that condenser $C40$ is still charged, the fifth sequence slit 49 now renders the fifth sequence

tube G_5 conductive, energizing relay Z_{oc1} of the carry-over unit, causing Z_{oc2} by discharge of condenser C_0 to close contacts $s71$, and putting capacitor C_{40} on the negative bus B. The capacitor C_{40} thus adds its charge to that of bus B, putting it on the grid of the non-conducting side of the next higher counting tube V_t which thereupon connects the corresponding clutch magnet. Slit 49, through tube G_5 , also energizes magnet Z_1 from A32 which shifts the stepping solenoid Z_1 , and shaft 105, one step. This is effected by slit 49 triggering G_5 which closes relay Z_{oc1} direct and Z_{oc2} by discharge of condenser C_0 thus putting a negative potential on C_{40} , causing this to discharge and applying a more positive potential to the grid of V_t . Both clutch magnet and shifting solenoid being thus actuated, the carry-over operation of adding one step to the next higher adding element is performed. It should be noted that the carry-over operation is prevented during the "totalling" and "printing operations," to be described hereinbelow, due to the fact that during these last mentioned operations, contacts $s42$ and $s32$ of relay Z_{op} are open.

The above description of the carry-over operation refers particularly to the situation when during an adding operation the adding element 145 progresses from its point nine to its point zero, on the floating home point of the reference element. The corresponding situation occurs in the case of subtraction when the home point of the subtracting disk leaves the zero point of the adding element 145 and progresses to the nine point of its adding element. So far as the relative positions of the commutator contacts $s1$, $s2$, $s11$ and $s12$ and $s3$ and $s13$ are concerned, there is no difference between the two situations, the commutator being in effect symmetrical, no matter whether $s2$ and $s3$ approach $s13$ and $s12$ from one side or the other. It will be remembered that FIG. 9 shows the superimposed commutator switch disks in the "adding" position when point nine of the adding disk coincides with the home point of the subtracting disk, further rotation of the adding disk bringing both zero points into coincidence. On the other hand, assuming that the relative position of the disks is as shown in FIG. 10, the adding disk is stationary and the subtracting disk advances (in the same direction), the relative position of the commutator contacts at the start is that indicated in FIG. 10, which shows that, as above stated, the relation of the contacts is for present purposes the same.

However, since switch $s52$ of solenoid Z_{os} has during the subtracting operation, connected the subtracting clutch magnets instead of the adding clutch magnets, the subtracting disk instead of the adding disk of the next higher order is turned one step, reducing that order by one digit, which is the proper operation in the situation.

It will be noted that, as explained above, the subtracting switching tube V_s remains conductive for energizing its clutch magnet throughout the time period when the effect of the fifth sequence slit prevails, because the subtracting operational mark extends over all five sequence slits triggering the tube at the passing of each sequence slit, so that any carrying-over operation in a subtracting step is properly finished without premature interruption.

One operational mark which initiates and controls subtracting is of sufficient length to provide for successive carry-over operations, as in the instance where a first carry-over step will cause simultaneously minus carry-over operations in a multiple of orders positioned to the left of that first order, as in the case of the so-called "fugitive one" which is discussed in detail in my above-identified patent, which also explains the simultaneous "carry-over" and "carry-on-carry" operations performed simultaneously with one and the same machine operation.

For that purpose, a contact $s5$ is located on the face of commutator switch disk 145 (FIGS. 7 to 10) at its

"9 count" at the "home" or "zero" position on disk 146 the contacts

$$\frac{s}{5}$$

and

$$\frac{s}{15}$$

10 are in contact one with the other. These two contacts will remain in circuit making relation so long as they are in this relative position.

The contact $s5$ on disk 145 is electrically connected from the condenser C_{40} through switch $s1$ on one order, to the contact $s11$ on the next order to the left which leads to point 321 on the grid circuit of the second order to the left. If in this sequence the second order to the left also shows a "9 count" then this same circuit will establish a through connection to the third order to the left. An example of this phase of the operation is presented in my above patent which also explains the initiation of total taking and printing wherein the herein described apparatus functions as follows.

15 It will be remembered that the printing unit above described with reference to FIGS. 11 to 14, has type wheels whose numbers run in a sense opposite to that of the corresponding numbers of the accumulator or adding wheels, for the purpose which will presently become apparent.

20 Since for totalling all code marks are black on the record strip, and since the printer solenoids and clutch magnets are now in circuit, together with the accumulator clutch magnets and solenoids, all these are simultaneously energized during the totalling operations.

25 With the type wheel in position "normal," the printer commutator contacts $s25$, and $s26$ of disk 233 are disconnected, resting in the space between the contacts $s22$ and $s23$ of the contacts of the opposite commutator disk 233 (FIGS. 11 to 14).

30 It will now be evident that, with all code marks effective as explained in my above patent, and with the operational mark "printing" retaining the printing tube V_t conductive to energize magnet Z_{op} , all adding disks and all printer wheels will advance due to the action of the solenoids Z_1 , Z_2 , Z_4 and Z_{p1} , Z_{p2} , Z_{p4} rotating shafts 105 and 205 (FIGS. 1, 2 and 11). This movement will continue until any one adding disk reaches its home position on the subtracting or reference disk. Then, commutator contacts $s4$ and $s14$ of accumulator disks

35 143 and 146 of the respective set, make connection. Commutator segment $s4$ leads to the minus bus B through contact $s41$ of solenoid Z_{op} which is now closed, and commutator segment $s14$ connects to the grid $g22$ of tube V_u , or that V tube whose accumulator disk has

40 reached the above mentioned home position. This immediately puts the grid on the negative bus B and renders the respective anode circuit non-conductive, cutting out the respective clutch magnets Z_a , Z_p . Therefore, the respective printer wheel and accumulator disk will immediately stop.

45 It should be noted that this stoppage is independent of the movement of the shifting solenoids Z_1 , Z_2 , Z_4 , Z_{p1} , Z_{p2} , Z_{p4} , which may continue to move if the solenoid in question happens to be one which defines more than one unit, such as solenoid Z_4 or Z_{p4} which, after having brought its accumulator or printer into zero position, might continue to advance through an angle of 108° , representing three number values.

50 Thus, assuming that any accumulator wheel was, when the totalling operation began, with its point n at the homing position, it will have turned $10-n$ steps before it comes to the above described stop, whereas the printer wheel, being inversely numbered, but turning in the same direction, will stop at n , that is the correct position for totalling and recording the total. All wheels whose zero adding wheel point has reached the home point of

the subtracting or reference wheel, are locked by the circuit through the segments $s4-s14$ of their commutators.

While, as mentioned above, the sequence solenoids complete their action regardless of the energization or de-energization of the respective clutch magnets at the reaching of the home position of any one zero point of the adding wheel, the fifth sequence slit, operating tube $G5$, energizes the hammer solenoid Zh , energizing the hammer 211 (FIG. 11) and printing the ledger card presented thereto.

The above operation leaves the accumulator disks with all zero points at home position, but not the type wheels.

The operation of re-setting the type wheels is performed without the aid of operational of other marks, by means of the printer commutators shown in FIGS. 12 to 14. The space between two sets of five sequence slits provides sufficient time for this operation.

Referring now particularly to FIGS. 11 to 19 and to my above-identified patent, it will be noted that normally, that is before the totalling operation begins, the commutator contacts $s25$ and $s23$ of the commutator disks, as shown in FIG. 14. As mentioned above, with the total switching tube Vp conducting through anode $a22$, contacts $s32$ and $s42$ of solenoid Zop are disconnected, and with them the commutator contacts $s25$ and $s26$, the latter being kept open so long as tube Vp is conductive as above described, that is, until an accumulator wheel zero point reaches home position. When, after the totalling operation is performed, the tube Vp becomes ineffective because conductive through the non-operative anode $a21$ and Zop de-energized, connection is made through $s22$, $s23$, $s26$, $s25$, which are now in contact since the printer wheels are not in the zero position, which alone corresponds to contacts $s25$ and $s26$ being positioned in the gap between the two other printer commutator contacts. This circuit is completed through contacts of relay Zop and through the appropriate connections between the commutator segments $s25$ and $s26$, as shown at Np in FIG. 20 of the above patent. It will be further observed that the above position of the printer contacts locks out the printer commutator during the totalling operation.

Now, with $s25$ on $s23$, $s26$ on $s22$, and $s32$ and $s42$ of Zop closed, the printer solenoids and clutch magnets are energized directly through the printer commutator, in circuit A— $s32$ — $A32$ — $s25$ — $s23$ — $A31$ — $R31$ — Zpu — $s22$ — $s26$ — $B12$ — $s42$ —B, independently of tubes G and V , advancing the printer wheels step by step until each wheel reaches the zero position, when segments $s25$ and $s26$ become disconnected from $s23$ and $s22$ respectively, and the respective clutch magnets are disconnected. Each printer wheel therefore stops at its proper normal position, namely with the zero type on the printing hammer.

The resistor $R31$ is inserted in this circuit in order to make it electrically equivalent to the corresponding tube control circuits which are otherwise utilized for energizing the respective clutching and shaft turning solenoids.

The accumulator disks are now with their zero points at the home point of each respective subtracting or reference wheel, the printer wheels are at zero position relatively to the recording device, the required adding, subtracting, carrying over and totalling operations have been performed and recorded, and the apparatus is ready for further operation.

It should be understood that the present disclosure is for the purpose of illustration only and that this invention includes all modifications and equivalents which fall within the scope of the appended claims.

I claim:

1. In apparatus of the type described, a magnetic actuating mechanism comprising base means, guide means supported on said base means, magnet means fast to said base means adjacent said guide means, magnetic core

means forming a gap with said magnet means, operator means mounted for movement in a first mode relatively to said guide means and having an engaging portion, actuating means having an armature portion in and movable

5 in a second mode transverse of said first mode within said gap and a coupling portion permanently within said engaging portion, a second magnet means magnetically coupled to said core means, and means for varying the relative strength of said second magnet means so as to reverse the flux in said gap, attraction of said armature portion to said first magnet means moving said coupling portion relatively to said base away from said operator means thereby to permit relative movement of said operator means and said actuating means in said first mode.

2. In apparatus of the type described, a magnetic actuating mechanism comprising base means, shaft means journaled on said base means, magnet means fast to said base means adjacent said shaft means, magnetic core means fast to said shaft means and forming a gap with said magnet means, operator means mounted on said shaft means rotatable relatively thereto and having an engaging portion, coupling means having an armature portion in and movable within said gap and a coupling portion permanently within said engaging portion, a second magnet means magnetically coupled to said core means and capable of counteracting the attraction of said first magnet means, and means for varying the relative effect of said magnet means, attraction of said armature portion to said first magnet means arresting said operator means relatively to said base and repulsion of the armature portion from the first magnet attaching said operator means to said core means, coupling the operator means to the shaft.

3. In apparatus of the type described, a magnetic actuating mechanism clutch comprising base means, shaft means supported on said base means, a magnetic means fast to said base means and surrounding said shaft means, magnetic core means surrounding said shaft means and forming a gap with said magnet means, operator means fastened to said base means, surrounding said shaft means and having an engaging portion and a contact portion, actuating means having an armature portion in and movable within said gap, a contact portion permanently within

40 said engaging portion, a second magnet means magnetically coupled to said core means, and means for varying the relative strength of said magnet means so as to reverse the flux in said gap, attraction of said armature portion to said first magnet means moving said operator

45 means relatively to said base tending to disengage said contact portion and repulsion of the armature portion from the first magnet means tending to engage said contact portions.

4. In apparatus of the type described, a magnetic actuating mechanism comprising base means, shaft means supported on said base means, magnet means fast to said base means and surrounding said shaft means, magnetic core means forming a gap with said magnet means, operator means rotatably mounted relatively to said shaft

50 means and having an engaging portion, actuating means having an armature portion in and movable within said gap and a coupling portion permanently within said engaging portion, a second magnet means magnetically coupled to said core means, and means for varying the relative strength of said second magnet means so as to

55 reverse the flux in said gap, attraction of said armature portion to said first magnet means moving said operator means relatively to said base.

5. In apparatus of the type described, a magnetic clutch mechanism comprising base means, a shaft journaled on said base means, a permanent magnet fast to said base means and loosely surrounding said shaft means, a magnetic core cylinder fast to said shaft means and forming a gap with said permanent magnet, operator

60 means relatively to said base.

6. In apparatus of the type described, a magnetic clutch mechanism comprising base means, a shaft journaled on said base means, a permanent magnet fast to said base means and loosely surrounding said shaft means, a magnetic core cylinder fast to said shaft means and forming a gap with said permanent magnet, operator

65 means relatively to said base.

7. In apparatus of the type described, a magnetic clutch mechanism comprising base means, a shaft journaled on said base means, a permanent magnet fast to said base means and loosely surrounding said shaft means, a magnetic core cylinder fast to said shaft means and forming a gap with said permanent magnet, operator

70 means relatively to said base.

8. In apparatus of the type described, a magnetic clutch mechanism comprising base means, a shaft journaled on said base means, a permanent magnet fast to said base means and loosely surrounding said shaft means, a magnetic core cylinder fast to said shaft means and forming a gap with said permanent magnet, operator

75 means relatively to said base.

9. In apparatus of the type described, a magnetic clutch mechanism comprising base means, a shaft journaled on said base means, a permanent magnet fast to said base means and loosely surrounding said shaft means, a magnetic core cylinder fast to said shaft means and forming a gap with said permanent magnet, operator

80 means relatively to said base.

10. In apparatus of the type described, a magnetic clutch mechanism comprising base means, a shaft journaled on said base means, a permanent magnet fast to said base means and loosely surrounding said shaft means, a magnetic core cylinder fast to said shaft means and forming a gap with said permanent magnet, operator

85 means relatively to said base.

13

means coaxially mounted on said shaft rotatable relatively thereto and having an engaging slot, coupling means having an armature disk in and movable within said gap and surrounding said shaft and a coupling portion permanently within said engaging slot, and a solenoid surrounding said core cylinder, attraction of said armature portion to said permanent magnet arresting said operator means relatively to said base and repulsion of the armature portion from the magnet coupling said

14

operator means to said core cylinder, attaching said operator means to said shaft.
